UNITED STATES PATENT OFFICE

113,309

DESIGN FOR A COMBINED STOOL PEDESTAL AND FOOT SUPPORT

Lawrence M. Michelson, Clayton, Mo.

Application December 22, 1938, Serial No. 81,949

Term of patent 7 years

To all whom it may concern:

Be it known that I, Lawrence M. Michelson, a citizen of the United States, residing at Clayton, in the county of St. Louis and State of Missouri, have invented a new, original, and ornamental Design for a Combined Stool Pedestal and Foot Support, of which the following is a specification, reference being had to the accompanying drawing, forming part thereof.

Figure 1 is a view in side elevation of a com-

bined stool pedestal and foot support embodying my design;

Figure 2 is a view in top plan; and

Figure 3 is a sectional view taken substantially on the line 3—3 of Figure 1 looking in the direction of the arrows.

I claim:

The ornamental design for a combined stool pedestal and foot support, as shown.

LAWRENCE M. MICHELSON.
